UNITED STATES PATENT OFFICE.

ABRAHAM ASHKENAS, OF BROOKLYN, NEW YORK.

FILE AND BINDER.

Application filed March 25, 1927. Serial No. 178,259.

This invention relates generally to improvements in files and binders adapted to support and maintain in assembled condition a plurality of leaves, pamphlets, journals or magazines.

The invention contemplates the provision of an article of the above-mentioned character wherein the assemblage of parts results in the production of a complete device adapted to bind together a plurality of leaves for convenient reference or reading.

The invention is further featured by means for maintaining the parts in assembled relation after the binding of leaves therein, said means being reversely operable for the purpose of separating certain parts in order to add another quantity of leaves.

A further object is to provide means directly connected to said leaves for binding the same between the parts of the holder or file.

A still further object is to provide means for detachably locking the parts together to prevent accidental separation during the handling thereof, such as for reading or other reference purposes and also functioning as additional means for pendantly supporting the same when not in use.

With these objects in view, together with others which will appear as the description proceeds, the invention resides in the novel formation, combination, and arrangement of parts all as will be described more fully hereinafter, illustrated in the drawings, and particularly pointed out in the claims.

In said drawings:

Figure 1 is an elevation of the device, certain parts being broken away for the sake of clearness.

Fig. 2 is an elevation of the top portion of the device which carries certain hooks and pins for effecting the assemblage of said device; and

Fig. 3 is a plan view of the other portion of the article.

Referring now more in particular to the accompanying drawings, wherein like characters of reference denote similar parts throughout the several views, let 5 denote generally my improved binder or holder, which comprises essentially the parts 6 and 7, somewhat similar in construction, and which for convenience may be termed the top and bottom portions respectively of the device.

Upon reference to Fig. 1, which illustrates the article in assembled position, it will be observed that one end of each of the portions 6 and 7 is arcuately formed, which unite to define a rounded semi-circular head portion when the parts are positioned as shown in said Fig. 1. The other extremities of the portions 6 and 7 are reduced, as indicated at 10 and 11 to form a convenient hand-hold during the portage of the device.

As indicated by the dot and dash lines in Fig. 1, the leaves or journals are to be carried between the two portions or members 6 and 7, and in order to provide the necessary space, each of said members is cut-away, as indicated at 12 and 13 in order to present the opening 14 indicated in said Fig. 1. The size of this opening is, of course, variable, depending on the size of the leaves or magazines, that is, as to width and thickness, but this matter may be lightly dealt with in view of the standardization of current journals and magazines now on public sale.

The means for directly binding the leaves between the holders comprises pins 15 and 16, which are carried by the part 6, and which extend therefrom an appreciable distance where their pointed ends slightly enter longitudinal slots 17 and 18 formed in said member 7.

These pins 15 and 16 may be inserted in suitable apertures in the several leaves prior to the assembling of parts 6 and 7 and may be easily removed therefrom in the event my device is used as a temporary filing means for subsequent binding.

I now call particular attention to the means for maintaining the parts 6 and 7 in assembled relation, and considering for the moment the top portion or member 6, illustrated in Fig. 2, it is noted that adjacent the extremities of said member are arranged depending hooked members 19 and 20, which are secured at their tops to said member, as indicated at 19^a and 20^a, in any approved manner. Each of said members 19 and 20 are provided with lateral projections 21 and 22, substantially flat at the base thereof but having their upper edges rounded over and inclined, as indicated at 23 and 24.

Considering now the assembling of the parts, without reference to the leaves therebetween, it will be seen in Fig. 3 that said

member 7 is provided with a spaced pair of thin slots 25 and 26, disposed centrally in the longitudinal axis thereof, each being arranged with a transverse pin 27, 28 passing therethrough, as indicated in Fig. 1. From the foregoing it appears quite obviously true that upon inserting the hooked members 19 and 20 into said slots 25 and 26 adjacent the left side thereof, a slight sliding movement of said part 6 with respect to part 7 causes the lateral portions 21 and 22 to engage the transverse pins 27 and 28, which ride upon the rounded edges 23 and 24 thereof to bind the parts in the position indicated in Fig. 1. Said parts 6 and 7 are just as readily disassembled by sliding back the part 6 until the hooked members are disengaged from the pins 27 and 28, whereupon said part 6 may be lifted bodily therefrom.

As previously pointed out the leaves, magazines, or journals are pierced by the pins 15 and 16 and when one or more have been secured in this position, the hooked members may be inserted in their respective slots 25 and bind the leaves in the opening 14. In view of the rounded disposition of said hooked members, as indicated at 23 and 24, a cam edge is provided upon which the pins 27 and 28 may ride in order to effect a tight clamping between the respective parts.

While I consider the cooperation between said hooked members and pins sufficient to maintain the parts in assembled relation, I prefer to provide secondary means in the form of a rotatable catch 30, which is insertible in the bore 29 of the part 6 and is provided with an eye 31 for hooking the holder to a suitable support. In Fig. 1, said catch 30 is shown with its offset 32 substantially abutting the lower member 7, and thus in the event said member 6 tends to slide upon its companion member 7, said offset abuts the end of the latter and maintains the parts together. When it becomes necessary to separate the members 6 and 7, the catch 30 may be rotated to bring said offset above the end of member 7 and member 6 may then be slid rearwardly to effect disengagement as aforesaid.

While the foregoing presents the invention in its preferred form it is to be understood that minor changes and alterations may be resorted to without departing from the spirit of the invention as defined in the appended claims.

I claim:

1. A binder comprising two members of similar form, which when united define an opening for the reception of leaves, a hooked member carried by one of said members and a transverse pin disposed in the other of said similar members, said hooked member and pin being adapted to slidably engage with each other to secure said similar members in position.

2. A binder of the class described comprising two members of similar form which when united define an opening for the reception of leaves, hooked members carried by the top member and depending therefrom and having a cam surface arranged on their upper edges and transverse pins mounted in the other of said similar members and adapted to be engaged by the cam surface of each of said hooked members to bind said similar parts together.

3. A binder of the class described comprising two members of similar form which when united define an opening therebetween for the reception of leaves, pins carried by the top member and depending from the bottom portion thereof through said opening, hooked members carried by said top member and depending therefrom and presenting an upper cam edge, transverse pins arranged in the bottom member and extending into vertical slots arranged therein, said cam surfaces adapted to engage said pins to bind the similar members together and rotatable catch means carried by the top member and having an offset portion adapted to engage the end of said bottom member to further secure the members in position and prevent backward sliding movement of said top member.

In testimony whereof I affix my signature.

ABRAHAM ASHKENAS.
